UNITED STATES PATENT OFFICE.

WILLIAM C. BAXTER, OF BEVERLY, MASSACHUSETTS, ASSIGNOR TO UNITED SHOE MACHINERY COMPANY, OF PATERSON, NEW JERSEY, A CORPORATION OF NEW JERSEY.

SHOE-JACK.

1,171,383.

Specification of Letters Patent.

Patented Feb. 8, 1916.

Application filed February 24, 1913. Serial No. 750,325.

To all whom it may concern:

Be it known that I, WILLIAM C. BAXTER, a citizen of the United States, residing at Beverly, in the county of Essex and State of Massachusetts, have invented certain new and useful Improvements in Shoe-Jacks; and I do hereby declare the following to be a full, clear, and exact description of the invention, such as will enable others skilled in the art to which it appertains to make and use the same.

The present invention relates to shoe supporting jacks and more particularly to jacks which are employed in connection with machines for leveling the soles of boots and shoes. It is desirable that a jack of this type shall be so constructed that it may accommodate shoes and long-legged boots of varying sizes and styles, that the adjustment 20 may be readily accomplished without requiring a high degree of skill, and that when properly adjusted the jack shall hold the shoe firmly during the operation of the machine.

The object of the present invention is to 25 provide a jack of this type which may be readily and accurately adjusted to accommodate with equal facility both shoes and long-legged boots of widely varying sizes and styles and which holds the boot or shoe 30 securely when positioned upon the jack.

With this object in view, the several features of the invention consist in certain novel features of construction, combinations and arrangements of parts, the advantages 35 of which will be obvious to those skilled in the art from the following description.

In the accompanying drawings: Figure 1 represents a side elevation of the preferred form of jack; Fig. 2 is a front elevation of the jack shown in Fig. 1; Fig. 3 is a section taken upon the line 3—3 of Fig. 1, looking in the direction of the arrows and illustrates the construction of the toe rest and adjusting mechanism; Fig. 4 is a detail illustrating the construction for supporting the last block upon the heel post; Fig. 5 is a detail showing upon an enlarged scale a plan view of the heel clamp; Fig. 6 is a detail showing a front elevation of the jack with the heel clamp removed, and illustrating the manner in which a long-legged boot is supported upon the jack; and Fig. 7 is a detail partly in section, showing upon an enlarged scale the mechanism for securing a vertical adjustment of the heel clamp.

The jack shown in the illustrated embodiment of the invention is employed in connection with a machine of the type disclosed in the U. S. patent to Winkley, No. 555,548, dated March 3, 1896, which is provided with a shoe supporting jack and leveling roll, and mechanism for automatically varying the relative longitudinal position and lateral inclination of the roll and jack. When operating upon long-legged boots it is 60 desirable that the upper of the boot be allowed to hang down loosely without interference with any portion of the jack in order to prevent marring or otherwise injuring the finished appearance of the upper. To this end the jack is provided with relatively long heel and toe posts which are pivoted together at their lower ends, the heel post having a free space completely surrounding it throughout substantially its entire length to enable the upper of a long-legged boot to loosely envelop the heel post when a boot is supported upon the jack. 65 The jack consists of a toe post 1 and a heel post 3, fulcrumed at 4 upon the lower portion of the toe post. The toe post is provided with an integral hub 5 which is loosely sleeved upon a rock shaft 6 and the jack is connected with the rock shaft and actuating mechanism in the usual manner. A 70 relative movement of the heel and toe posts toward and from one another is secured by an adjusting member 9. The member 9 is provided with a threaded portion 10 which engages with a split nut 11 swiveled in an arm 12 formed integral with the hub 5. The opposite end of the adjusting member passes 75 through a head 14 which is swiveled upon an arm 15 spaced away from and formed integral with the heel post. The adjusting member is retained against longitudinal movement relative to the head 14 by a collar 16 and a hand wheel 17 secured to the member upon opposite sides of the head. With 80 this construction, by a simple rotation of the adjusting member the heel post is moved to and from the toe post to readily adjust the jack for different sizes of shoes. With 85 this type of machine the most efficient leveling action is secured when the shoe is supported in an operative position with its sole lying substantially in a horizontal plane, as when the shoe is supported in this position the same pressure is exerted upon different 90 portions of the sole. In the majority of 95 100 105 110

lasts the depth of the last varies proportionately with the length, and to compensate for this variation in depth the last block when adjusted for smaller sizes of shoes must have both an inward and upward movement toward the toe post. In the present invention this is accomplished by forming the heel post as a curved arm so arranged that upon adjusting the heel post 10 toward the toe post it is moved upwardly as well as inwardly, compensating for the decrease in the depth of the last and avoiding the necessity of a separate vertical adjustment of the last block each time that the 15 jack is adjusted for varying sizes of shoes.

The toe of the shoe is supported upon a toe rest 20 which is detachably connected to a toe rest support 21 through a vertical spindle 22 and a pair of depending ears 23 20 engaging with opposite sides of the toe rest support. A bodily vertical adjustment of the toe rest relative to the support is secured by a wedge 25 slidingly mounted upon the support and interposed between the support and the lower face of the spindle 22, as shown clearly in Fig. 3. The wedge is adjusted horizontally to raise and lower the toe rest by an adjusting member 27 threadedly engaging with the wedge and 25 journaled in an arm 28 formed integral with the toe rest support 21. The adjusting member 27 is retained against longitudinal movement in the arm 28 and is provided with a hand wheel 29 which enables 30 it to be conveniently manipulated by the operator. The toe rest is provided with a removable toe cap 30 which is connected with the rest by a spindle 31 and pair of depending ears 32 to prevent angular movement of the toe cap relative to the rest and to allow the toe cap to be readily removed and replaced by one of another form. It 35 is desirable that the toe rest be adjusted to accommodate lasts of varying angularity, and to this end the toe rest support 21 is 40 slidingly mounted in arcual ways 33 formed in the upper portion of the toe post 1 so that the toe rest is adjustable about an axis lying substantially in the work engaging 45 surface of the rest. The rest is adjusted by a worm 35 journaled in the toe post and meshing with a gear segment 36 formed upon the under face of the support 21. The outer end of the worm 35 has a knurled 50 wheel 37 secured thereto which may be conveniently operated to adjust the toe rest angularly without causing a bodily displacement of the work engaging surface of the rest. The upper portion of the toe post 55 is provided with an inclined face 39 which is normally contiguous to the surface of the sole and forms a receiver for the leveling roll in a manner well known to those skilled 60 in the art.

65 The heel portion of the last is supported

by a last block 40 fulcrumed centrally upon the heel post at 42 and having the usual last spindle 41. As shown in Fig. 4, the last block is supported by a pair of flat plates 44 secured in recesses formed in opposite sides of the heel post and extending upwardly to form bearings for opposite sides of the last block. The last block is rocked to clamp the shoe upon the jack by an actuating rod 46 slidingly mounted in the heel post and bearing upon the under side of the last block at one side of the fulcrum. The rod 46 is moved in the direction of its length to impart a clamping movement to the last block by an actuating shaft 47 journaled in the upstanding arm 15 and extending into a position conveniently accessible to the operator. The actuating shaft 47 has a beveled gear 52 secured to its lower end meshing with a beveled gear 53 which is mounted upon a cross shaft 55 having a spiral gear 56 secured upon its opposite end. The gear 56 meshes with a second spiral gear 57 which threadedly engages with the lower end of the rod 46, as shown clearly in Fig. 1, so that upon a rotation of the actuating shaft 47 the rod 46 is moved in the direction of its length to rock the last block into a clamping position. The last block is returned to its initial position by a 95 plunger 60 bearing upon the under side of the last block opposite the rod 46, and a spring 61 which engages beneath the plunger.

In leveling machines of the rolling pressure type it is customary to apply the pressure successively to opposite margins of the sole and this transference of the pressure tends to rock the shoe laterally upon the last, which movement not only enlarges the last pin hole and prevents the firm clamping of the shoe, but impairs the efficiency of the leveling operation. To hold the shoe firmly during the leveling operation the jack of the present invention embodies a clamp which tightly embraces the heel portion of the shoe and rigidly maintains the shoe in upright position, preventing any lateral movement of the shoe due to the action of the leveling device. The heel clamp is supported upon the upper end of a rod 65 fulcrumed at 66 on a lateral extension 67 of the heel post. The clamp is freely movable into an operative position and is positively locked in this position by a pawl 69 slidingly supported upon the heel clamp and engaging with a stationary ratchet toothed plate 70. The plate 70 is fastened in any suitable manner to an arm 71 extending from the arm 15 and secured thereto by bolts 72. The pawl and ratchet are disengaged to remove the heel clamp from the shoe by a curved finger lever 75 pivoted upon the heel clamp at 76 and loosely connected to the pawl by a bolt 77. The opposite end of the bolt is connected to 130

a tension spring 73 which normally serves to press the pawl into engagement with the ratchet plate. The finger lever projects into a position conveniently accessible to the hand of the operator so that the pawl may be disengaged and the heel clamp swung back into an inoperative position by the employment of one hand. The heel clamp shown in the illustrated embodiment of the invention consists of a plurality of separate clamps engaging with the back and sides of the counter, and to enable the clamp to fit varying sizes and styles of lasts it is capable of a bodily vertical and angular adjustment 10 and an adjustment of the side counter-clamps toward and from one another. The counter-clamps are mounted upon a head 79 which is provided with a standard 78 rotatably mounted in a support 80 and normally clamped in the support by a transverse clamping bolt 81 having a recessed portion engaging with the side of the standard, as shown clearly in Fig. 7. The bolt 81 is provided with a hand wheel 82 threadedly connected to the clamping bolt and arranged to draw the side of the recess against the standard to clamp the standard into position in a manner well understood. The clamping head is adjusted vertically by a screw 83 threadedly engaging with the head and provided with a knurled operating nut 84. The screw is retained against longitudinal movement by a T-shaped head 85 which projects into a correspondingly shaped curved recess formed in the support 80, which, as shown in Fig. 5, is of greater length than the width of the T-shaped head to allow a bodily angular adjustment of the heel clamp. The counter-clamps are shown clearly in Fig. 5 and consist of a clamp 90 engaging with the back of the heel and a pair of clamps 91 engaging with opposite sides of the heel, each of the clamps being faced with suitable yielding material to avoid marring the upper of the shoe. The clamp 90 is formed integral with the head 79 and each of the clamps 91 is pivotally supported upon an arm 92 formed as a bell crank lever fulcrumed upon the head at 94 and having a toothed segment 95 meshing with an adjusting worm 96. The worm 96 is formed upon the inner end of a shaft 97 journaled in the head 79 and having a hand wheel 98 secured to its outer end by means of which the shaft is rotated to cause a movement of the clamps 91 toward and from one another.

The preferred mode of operation of the jack is as follows:—The shoe to be operated upon is first positioned upon the last block with the upper of the shoe or long-legged boot, as the case may be, hanging down loosely around the heel post. The heel post is then adjusted relative to the toe post to properly seat the toe of the shoe upon the

toe rest, and the shaft 47 is then actuated to clamp the shoe firmly in position on the jack. Before clamping the shoe in position the toe rest may be adjusted angularly, if so desired, to cause the toe of the shoe to engage closely with all portions of the toe cap. After the shoe has been clamped upon the jack the heel clamp is swung inwardly by the operator until the counter-clamp 90 engages with the back of the heel, in which position it is automatically locked in position by the pawl and ratchet locking mechanism. Prior to this locking of the clamp in position, it may be adjusted either vertically or angularly to properly engage with the heel portion of the shoe. After the heel clamp is properly positioned, the hand wheel 98 is manipulated to move the side counter-clamps together and grip the sides of the heel, rigidly maintaining the shoe in an upright position and preventing any lateral movement.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:—

1. A shoe supporting jack having, in combination, a toe post, a heel post fulcrumed upon the toe post, an adjusting member connecting the toe and heel post to vary the distance between the two, a toe rest mounted upon the toe post and having provision for adjustment about an axis lying substantially in the work engaging surface of the toe rest, a last block supported upon the heel post, and mechanism mounted upon the heel post for actuating the last block to clamp the shoe upon the jack.

2. A shoe supporting jack having, in combination, a toe post and a heel post arranged to support a shoe with the bottom lying substantially in a horizontal plane, and mechanism for adjusting the heel post toward the toe post and for simultaneously imparting a vertical movement to the heel post to decrease the vertical distance between the heel post and toe post and enable lasts of varying length and depth to be properly jacked.

3. A shoe supporting jack having, in combination, a toe post, a heel post fulcrumed upon the lower portion of the toe post and arranged to swing inwardly and upwardly toward the toe post to accommodate lasts of varying length and depth, and mechanism for adjusting the heel post toward and from the toe post.

4. A shoe supporting jack having, in combination, a heel post, a toe post, mechanism for securing a relative movement of the heel

and toe posts toward and from one another, a toe rest supported in curved ways upon the toe post, a worm journaled upon the toe post, and means conveniently accessible to the operator for actuating the worm to adjust the toe rest about an axis lying substantially in the surface of the sole.

5. A shoe supporting jack comprising a toe post, a toe rest support slidingly mounted in curved ways on the toe post, a toe rest detachably connected to the support, mechanism for adjusting the support angularly about an axis located substantially in the work engaging surface of the toe rest, and 15 a wedge interposed between the toe rest and support for securing a bodily vertical adjustment of the toe rest.

6. A shoe supporting jack having, in combination, a toe post, a heel post, a last block 20 pivoted upon the heel post, an actuating rod slidingly mounted in the heel post and connected with the last block, and mechanism for actuating the rod to rock the last block comprising an actuating shaft journaled in 25 the heel post and having its upper end conveniently accessible to the operator, and connections between the actuating shaft and rod to impart a longitudinal movement to the rod upon a rotation of the shaft.

30. 7. A shoe supporting jack having, in combination, a toe post, a heel post, a last block supported upon the heel post, mechanism for rocking the last block to clamp the shoe upon the jack, a heel clamp fulcrumed upon the heel post, means for locking the heel clamp in operative position, and means for adjusting the heel clamp to accommodate 35 shoes of different sizes.

8. A shoe supporting jack, having in com-

bination, a toe post, a relatively long heel 40 post having a free space completely surrounding it throughout substantially its entire length to allow the upper of a long-legged boot to hang down loosely and envelop the heel post, an upstanding arm secured to the lower end of the heel post, and jack adjusting mechanism supported in the upper end of the arm conveniently accessible to the operator.

9. A shoe supporting jack having, in combination, a toe post, a heel post, means for securing a relative adjustment of the toe and heel posts, a heel clamp having provision for bodily vertical and angular adjustments, and means for locking the heel clamp 55 in operative position against the shoe during the operation of the machine.

10. A shoe supporting jack, having in combination, a toe post, a heel post, a heel 60 clamp having provision for a bodily angular adjustment in a plane substantially normal to the heel post, and means for locking the heel clamp in operative position against the shoe.

11. A shoe supporting jack comprising a 65 heel post, and a heel clamp co-operating therewith and comprising a pair of counter-clamps arranged to engage opposite sides of the heel of a shoe, pivoted arms supporting the counter-clamps, an adjusting member operatively connected with the arms, and means for rotating the adjusting member to simultaneously move the counter-clamps toward and from one another.
